UNITED STATES PATENT OFFICE.

ARTHUR R. FISHER, OF NEW YORK, N. Y.

COLON-IRRIGATOR.

1,211,928.

Specification of Letters Patent.

Patented Jan. 9, 1917.

Application filed March 25, 1916. Serial No. 86,637.

To all whom it may concern:

Be it known that I, ARTHUR R. FISHER, a citizen of the United States, residing at New York, in the county of New York and State of New York, have invented new and useful Improvements in Colon-Irrigators, of which the following is a specification.

This invention relates to colon irrigators, and has for one of its objects the provision of an irrigator of the kind whereby a rectal anesthesia may be performed in a sanative manner.

The particular object of this invention being to provide an instrument for the administration of anesthetics by the rectum to the colon, or large intestine, continuous from the ileum to the rectum; and to this end the irrigator consists of a flexible cylindrical body having an inflexible guard piece and a flexible applicator tube, longitudinally movable therethrough.

Another object of the invention is to produce an irrigator of the character mentioned wherein provision is made to permit the return flow of the wasted anesthetic.

Other means is provided to prevent an accumulation between the applicator tube and the walls of the cylindrical body, for the maintenance of a clear drain passage for the return flow of the wasted anesthetic.

With these objects in view, and others which will appear as the nature of my invention is better understood when the following description is read in connection with the accompanying sheet of drawing, in which:

Figure 1, is a perspective view of my improved irrigator. Fig. 2, is a central longitudinal sectional view thereof. Fig. 3, is a transverse sectional view, on the line 3—3 of Fig. 2. Fig. 4, is an end elevation.

Referring now to the drawing in detail, the numeral 1, designates a cylindrical body which is made, preferably, of some resilient material with a proper quality of stiffness and yet having a fine elastic quality. The mentioned cylindrical body is provided with a bore 2, and a threaded liner 3, adapted for threading engagement with the reduced thread end portion of an inflexible guard piece 4. The mentioned guard piece 4, has a bore 5, which alines with the bore 2, of the cylindrical body 1, and the said bore 5, is restricted as at 6, to snugly fit the flexible applicator tube 7. The tube 7, is of a smaller diameter than the diameters of the alining

bore 2, and the large portion of the bore 5, the purpose of which will be hereinafter fully explained.

The cylindrical body 1, at the end opposite to that end having the guard piece 4, is provided with diametrically opposite passages 1^a and diametrically opposite tube engaging portions 1^b, and at the same end the said cylindrical body is apertured at diametrically opposite points as at 8. The guard piece 4, is provided with a nipple 9, and a discharge duct 10, which communicates with the nipple 9, and bore 2. Connected to the nipple 9, is a rubber tube 11, with a bulb 12. The flexible applicator tube 7, is provided with an opening 13, at the extreme end thereof, and other openings 14, are provided in the side wall of said tube 7. The said tube 7, may be of any suitable length and is in practice connected with a vessel which contains the anesthetic, as ether, or any other medical solution that may be desired for the administration.

In practice the cylindrical body 1, is properly applied, the guard piece 4, serving as a closure against the return flow of the wasted anesthetic, which therefore, on its return passes through the apertures 8, into the bore 2, thence into the discharge duct 10, into the tube 11, with which it may be directed into a vessel for that purpose. In the performance of the anesthesia, the anesthetic is made to flow through the flexible applicator tube 7, and any or all the affected parts of the mucous membrane of the colon may be administered to, by reason of the longitudinal movement which may be imparted to the tube 7, relatively to the body 1, such feature is particularly advantageous, if a sanative administration is to be performed, moreover, and owing to the difference of the tensile qualities of the cylindrical body 1, and the applicator tube 7, that is to say, the fact that the cylindrical body 1, is less pliant than the applicator tube 7, the irrigator may be more readily applied for use, without causing any undue pain, as provision is necessarily made for the slight and gradual flexing of the parts. The cylindrical body 1, may also flex toward the applicator tube 7, owing to the space provided by the bore 2.

It is thought that the nature and advantages of the invention may be fully understood from the foregoing description, and that while I have shown and described

the preferred form of the invention, it is to be understood to cover all changes and variations within the scope of the invention and the claims hereto appended.

5 I claim:—

1. A colon irrigator, comprising a flexible cylindrical body having an inflexible guard piece, and a flexible applicator tube longitudinally movable therethrough as and for 10 the purpose specified.

2. A colon irrigator, comprising a flexible cylindrical body having a bore therein; an inflexible guard piece connected to the cylindrical body at one end, and having a discharge duct which communicates with said bore; apertures in the side walls of the cylindrical body at the other end thereof, the said bore, discharge duct and apertures constituting a drain passage, and a flexible applicator tube longitudinally movable through the inflexible guard piece and the flexible cylindrical body, as and for the purpose specified.

3. A colon irrigator, comprising a flexible cylindrical body having an inflexible guard piece at one end; and a flexible applicator

tube of a greater degree of tensility than the cylindrical body, the said tube being longitudinally movable through the cylindrical body and the guard piece, alining bores in 30 the cylindrical body and the guard piece, said bores being of a greater diameter than the exterior diameter of said tube, the bore of said guard piece being restricted for a portion of its length to snugly fit the applicator tube at any portion in its length; and tube engaging portions of the cylindrical body engaging said tube around a portion of its circumference to provide passages at the extreme end of said cylindrical body, said 40 body having apertures in the side walls thereof; a nipple on said guard piece, having a discharge duct therein, which communicates with the bore of said guard piece, and a drain tube connected with said nipple, 45 as and for the purpose specified.

In testimony whereof I, affix my signature in presence of two witnesses.

ARTHUR R. FISHER.
